UNITED STATES PATENT OFFICE.

ALFRED L. LAWSON, OF CHICAGO, ILLINOIS, ASSIGNOR OF ONE-HALF TO GEORGE S. WELCH, OF CHICAGO, ILLINOIS.

AMALGAMATOR.

1,067,352.

Specification of Letters Patent.

Patented July 15, 1913.

Application filed September 14, 1911. Serial No. 649,264.

To all whom it may concern:

Be it known that I, ALFRED L. LAWSON, a citizen of the United States, residing at Chicago, in the county of Cook and State 5 of Illinois, have invented a certain new and useful Improvement in Amalgamators, of which the following is a full, clear, concise, and exact description, reference being had to the accompanying drawings, forming 10 a part of this specification.

My invention relates to amalgamators and has for its object the provision of improved apparatus of this character.

My invention may be carried out in various forms, but in this application I have set forth one specific form of carrying out my invention without intending of course to limit myself to such specific form.

My invention has more particular reference to apparatus for separating gold and silver or compounds thereof from ore through the use of a mercury bath.

One feature of my invention is the violent projection of the ore into the mercury 25 to submerge the same therein, while yet at the same time maintaining a placid condition of the mercury on its surface.

In the general form herein shown I introduce the ore into the apparatus and force 30 it through a portion of the apparatus by the agency of a fluid jet which may preferably be of acid-neutralizing characteristics. The mixture is forced into the mercury bath and suitably deflected in such manner as 35 not to disturb the substantial placidity of the mercury bath. The metals which are desired to separate being heavier than mercury fall to the bottom and the residue rises to the surface of the mercury from 40 whence the overflow is carried through additional mercury baths, all as will be more clearly apparent from the specific description of one form of my invention which I will now set forth in connection with the 45 accompanying drawings, in which:

Figure 1 is a sectional view of a portion of an amalgamator constructed in accordance with my invention; Fig. 2 is a sectional view on lines *a—a* of Fig. 1 with the addition 50 of apparatus omitted from Fig. 1; Fig. 3 is an enlarged view of a portion of the apparatus shown in Fig. 2, and: Figs. 4 and 5 are details of construction.

Referring more specifically to Fig. 1, I 55 set forth a bowl 1 having the steam jacket

2, all supported upon legs 3, 3. The steam jacket 2 is formed between the walls of the bowl 1 and an outer inclosing wall 4. The bowl 1 is lined with a lining of glass 5, a suitable bushing 6 being provided at the lower orifice. A pipe 7 leads the steam into the steam jacket 2 and a pipe 8 leads it therefrom. Mercury 9 filled to the level shown is provided in this bowl. The lower orifice is extended into a tube 10 provided with a valve 11 so that the bowl 1 may be emptied of its contents if desired. An annular chamber 12 is provided around the top portion of the bowl 1 and is filled with mercury 13 to the level shown. Spouts 14, 14 lead from the bowl 1 to carry the overflow as will appear hereinafter and discharge the same into channels 15 preferably of the silver coated covering variety, which channels 15 unite to form a spout 16 which discharges this overflow into the second portion of the apparatus consisting of the separating device 17. A tube 18 extends through the steam jacket and opens into the interior of the bowl 1, which tube 18 is bent as shown more clearly in Fig. 5, and is adapted to be rotated so that the tube or outlet portion of this tube may be lowered to any given position by rotation so as to maintain the mercury 9 within the bowl 1 at any given predetermined level. The same general character of construction is utilized in connection with the annular groove 12 by means of the tube 19 which is 50 also rotatable so that its upper orifice may be adjusted to the height to be occupied by the mercury in the groove 12. A circular column 20 mounted in two halves is supported by means of the arms 21 on the bowl 1. Within the column 20 is a second column 22 closed at the top and held in spaced relation to the column 20 by means of arms 23. The column 20 has a flaring bottom wall 24 substantially wider than the open orifice of the column 20. A plurality 55 of tubes 25 are fastened to the hollow casing 26 and communicate with the interior thereof and these tubes 25 project downwardly into the space between the columns 20 and 22. A tube 27 supplies fluid preferably of an acid-neutralizing character under pressure to the chamber 26 so that this fluid under pressure may issue from the lower orifice at 28 of said tubes 25. The ore is dropped into the upper flaring mouth 29 60

of the column 20 and falls by the action of gravity until it reaches the lower extremities 28 of the tubes 25 where the pressure of the fluid issuing from said tubes forms a jet to force the ore against the flaring end 24 of the column 22 and into the mercury bath, distributing the same over a large area, but introducing this ore at a sufficient depth so as to maintain the comparative placidity of the mercury surface. The ore which is to include metals heavier than mercury, or whatever other substance used in place of mercury, is thus thrown violently into the mercury bath and the materials heavier than the liquid which in this instance is mercury fall to the bottom and congregate about the lower orifice of the bowl 1. The heavier materials then enter the pipe 8 and rest there, and may be withdrawn through the agency of the valve 11 as desired. It will also be noted that these heavier materials by falling below the flaring mouth 24 are protected from the violent movement of fresh incoming ore as the same is forced out through the lower orifice of the column 20.

The steam jacket 2 is used to heat the mercury so as to prevent flouring and also to increase its fluidity and also to lower the specific gravity if certain metals such as gold and silver are to be separated.

Before introducing the ore into the mouth 29, it is preferably ground so as to pass through a sieve of one hundred mesh. It will of course be understood that the liquid to be used depends upon the specific gravity desired and the specific gravity of the metals or compounds thereof which are to be separated by this liquid. The gold and silver or other metals which it is desired to separate falling to the bottom of the bowl 1, the remaining portion of the ore is buoyed to the top of the mercury and rests on the surface until it overflows over the extended wall 30 of this bowl and on top of the mercury within the annular groove 12. Certain metals which have been carried over the top of the wall 30 may drop to the bottom of the mercury trough 13, but the greater portion of the residue travels through the spouts 14 into the troughs 15 and through the spout 16 into the auxiliary separator 17. This auxiliary separator which is shown in Fig. 2 and a cross-section of which is shown in Fig. 3 consists practically of a trough having a bottom wall 31, side walls 32, 32 and an end wall 33, there being no end wall at the lower portion of this separator 17

(Fig. 2). The bottom wall 31 is provided with a plurality of troughs 34, 34 which contain mercury 35 to the level shown. These troughs are provided with baffle plates 36 are shown more clearly in Fig. 3. A steam coil 37 having preferably three legs in each trough serves to heat the mercury for the same purpose as outlined in connection with the mercury in the bowl 1. A pipe 38 having transverse pipes 39 serves to furnish fluid under pressure through the pipes 39 and out of orifices 40, to thereby create a jet 70 downwardly on the entering side of each trough 34, as shown more clearly in Fig. 3. The residue issuing from the spout 14 having passed through the spout 16 is depressed on the plate 31 and in its movement over the separator 17 reaches the first trough 34 where this residue is forced by means of the jets issuing from the orifices 40 into the first mercury bath. The metals designed for separation again fall to the bottom and residue ore is carried over the baffle plate 36 to the next trough 34, and thus it is carried successively through the various troughs 34 until it reaches the portion 41 of the baffle plate 31 from whence this residue is supposed to be free from the metals designed for separation and from whence it may be discharged from the machine. Rotatably mounted pipes 42 control the level of the mercury in the troughs 34 similarly to the pipes 18 and 19.

The above explanation will serve to illustrate one form of carrying out my invention, and as I am not limiting myself to this particular construction, my invention being capable of a variety of different uses and modifications.

What I claim as new and desire to secure by Letters Patent is:

In apparatus of the character described the combination with a tank, of a tube having an upper flaring mouth projecting within said tank, a second tube closed at its upper end and having a lower flaring mouth within said first aforesaid tube and projecting below the same, and a plurality of ducts extending between the said two tubes for forcing liquid into the space between the said tubes.

In witness whereof, I hereunto subscribe my name this 7th day of September, A. D. 1911.

ALFRED L. LAWSON.
